UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

CONTACT BRUSH AND HOLDER THEREFOR

Application filed December 26, 1923. Serial No. 682,790.

The present invention relates to certain new and useful improvements in contact brushes and holders therefor, and particularly to brushes of the class adapted to use in electric controllers to contact with the segments of the controller cylinder and thereby establish electrical connections between the conductors of an electric locomotive to form circuits suitable to control the 10 actuation of the motors thereof.

It is the especial object of this invention to provide an improved mechanism of the class described which shall be reliable and efficient in service and simple and economical 15 to manufacture.

The means whereby I attain this object are fully set forth in the following specification reference being had to the accompanying drawings of which—

20 Fig. 1 is a side elevation of the preferred embodiment of my invention.

Fig. 2 is a front elevation of the device illustrated in Fig. 1.

Fig. 3 is an end elevation of the device 25 illustrated in Figs. 1 and 2.

Fig. 4 is a transverse section taken along the line IV—IV of Fig. 1.

Fig. 5 is a detail of the tension spring abutment.

30 Figs. 6 and 7 are respectively front and side views of the contact brush disassociated from its holder.

Like numerals refer to similar parts in the several figures.

35 In the drawings the numeral 1 refers to the insulating foundation to which are secured, by suitable bolts 2, a plurality of brush holders 3. The foundation 1 is a part of the framework of an electric controller, but as the general arrangement of such controllers is well 40 understood by those skilled in the art, and as those matters form no part of the present invention, full description and illustration of them is not thought to be required at this time. As all of the brush holders are alike 45 illustration of one is thought to suffice.

The brush holder 3 consists of a metallic body having a flat brush supporting surface 4 adapted to engage the flat face of the brush 50 to hold it in position to contact with the

segment of the controller cylinder which is indicated by the dotted lines at 5 in Fig. 1 of the drawings. The brush consists of a straight copper bar 6 preferably flat and of rectangular cross section, to the outer end of which is attached a copper contact tip 7 adapted to form a fair bearing upon the contact segment 5 of the controller cylinder. A flange 8 projecting from the body of the brush holder and extending above the supporting surface 4 is adapted to engage the inner end of the brush bar 6 to prevent its longitudinal movement when contact is established with the moving segments 5. Other flanges 9 and 10, formed on the body of the brush holder, are adapted to engage the lateral edges of the brush bar 6 to prevent its lateral displacement, but these flanges are so positioned as to permit freedom of movement of the brush bar perpendicular to the supporting surface 4. Midway the length of the brush bar 6 there is formed a longitudinally elongated aperture 11 through which projects a stud 12 which is attached to the forward extension 13 of the brush holder, and the proportions of these parts are such that the stud 12 affords no restraint to either lateral or longitudinal movement of the brush bar 6. Fixed to the stud 12 near its outer end is a transverse pin 14 which projects at both sides of the stud, and is adapted to cooperate with the slots 15 formed in the thumb nut 16 to produce a bayonet joint by which said thumb nut is removably secured to said stud. A compression spring 17 encircling the stud 12 abuts against the brush bar 6 and the thumb nut 16 to resiliently hold the brush bar 6 in contact with the supporting surface 4 of the brush holder and the segment 5 of the controller cylinder. An adjusting screw 18 threaded through the brush bar 6 is adapted to engage the extension 13 of the brush holder to adjustably limit movement of the contact tip 7 towards the controller cylinder, and a spring 19 secured to the brush bar 6 engages the head of the screw 18 to hold it in adjusted position. A terminal binding post 20 which is mounted upon the insulating base 1, adjacent to but insulated from the brush holder, is connected 100

to the conductor 21 of the circuit to be controlled, and a flexible conductor 22 electrically connects the brush bar 6 with the binding post 20 without impairing the freedom of movement of the brush bar.

5 By the construction above described I have produced a controller brush and holder of great reliability and efficiency in service, convenience of manipulation, and simplicity of 10 construction, from which is completely eliminated the destructive effects of electric currents passing through either the tension spring or the pivotal support of the brush, and I have attained extreme flexibility of 15 support by which is insured perfect contact between the brush and controller segment, coupled with convenience of removal and replacement of the brush, and assurance of its proper pressure upon the contact segment of 20 the controller.

What I claim is:—

1. In an electric controller, the combination 25 with a brush holder, of a brush comprising an elongated metallic bar, a stud projecting from said brush holder transversely of said bar, an abutment removably attached to said stud by a bayonet joint, and a spring interposed between said stud and said bar to hold the latter in operative position upon 30 said brush holder.

2. In an electric controller, a brush comprising an elongated metallic bar having a medial aperture, and a brush holder comprising two integrally formed seating portions 35 for the bar, one of said seating portions comprising an abutment flange for the rear end of the bar and a lateral abutment flange for that end of the bar on each side thereof, the other seating portion being disposed at 40 the medial portion of the bar and comprising an abutment flange at each side of the bar, a pin extending through the last-named seating portion and said medial aperture, abutment means on said pin beyond the bar, and 45 a spring interposed between said abutment means and bar whereby the latter is urged toward the two seating portions.

3. In an electric controller, a brush comprising an elongated metallic bar having a 50 medial aperture, and a brush holder comprising two integrally formed seating portions for the bar, one of said seating portions comprising an abutment flange for the rear end of the bar on each side thereof, the other 55 seating portion being disposed at the medial portion of the bar and comprising an abutment flange at each side of the bar, a pin extending through the last-named seating portion and said medial aperture, abutment 60 means on said pin beyond the bar, and a spring interposed between said abutment means and bar whereby the latter is urged toward the two seating portions, said brush holder having a face on its side opposite the 65 bar adapted to be secured against a support-

ing member, said face and bar diverging toward the forward end of the latter.

In testimony whereof I have hereunto set my hand.

NILS D. LEVIN.
